**PRISM HOLDER FOR LASER BEAM REFLECTION
ON ELECTRICAL SURVEYING INSTRUMENTS**

James F. Buckley, Huntington Beach, Calif., assignor to
Pomco Enterprises, Inc.

Filed Jan. 12, 1972, Ser. No. 217,411

Term of patent 14 years

Int. Cl. D16—06

U.S. Cl. D57—1 E

FIG. 1 is a perspective view of the prism holder for laser beam reflection on electrical surveying instruments showing my new design;

FIG. 2 is a rear view of the prism holder for laser beam reflection on electrical surveying instruments along lines 2—2 of FIG. 1;

FIG. 3 is a partially sectioned view of the prism holder for laser beam reflection on electrical surveying instruments along lines 3—3 of FIG. 2;

FIG. 4 is a bottom view of the prism holder for laser beam reflection on electrical surveying instruments along lines 4—4 of FIG. 2;

FIG. 5 is a front elevation view of the prism holder for laser beam reflection on electrical surveying instruments along lines 5—5 of FIG. 4; and,

FIG. 6 is a side elevation view of the prism holder for laser beam reflection on electrical surveying instruments along lines 6—6 of FIG. 5.

I claim:

The ornamental design for a prism holder for laser beam reflection on electrical surveying instruments, substantially as shown.
